UNITED STATES PATENT OFFICE.

JAMES B. MORFITT, OF SHELDON, IOWA.

CRUTCH TIP.

Application filed June 27, 1923. Serial No. 648,133.

To all whom it may concern:

Be it known that JAMES B. MORFITT, a citizen of the United States, residing at Sheldon, in the county of O'Brien and State of Iowa, have invented certain new and useful Improvements in Crutch Tips, of which the following is a specification.

This invention relates to improvements in crutch tips.

10 It is a well known fact that the ordinary rubber crutch tip is liable to slip on icy and wet surfaces, although it is efficient under other conditions. It has been proposed to provide spur attachments for crutches which 15 will insure against slipping of the crutch on wet or icy surfaces, but such attachments are ordinarily difficult to apply and remove, and if not removed, are liable to mar the floor surface or tear or otherwise injure the floor 20 covering when the user of the crutch passes indoors. The present invention therefore has as its primary object to provide a crutch tip which may be immediately conveniently adapted for use under different conditions as 25 occasion requires, the tip embodying a resili- 30 ent and relatively soft pad which is best adapted for indoor use and for outdoor use when the street surfaces are free from moisture or ice, and a spur member which may be moved into and out of active position and which, when in active position will insure 35 against slipping of the crutch upon wet or icy surfaces.

Another object of the invention is to so 35 construct the attachment that in changing from one anti-slipping means to the other, it will be unnecessary to remove any parts thereby avoiding the annoyance of having to carry such removed parts about in one's 40 pockets.

Another object of the invention is to so construct the spur member of the attachment that when adjusted to the desired position, it may be firmly secured in a manner to insure 45 against displacement.

In the accompanying drawings:

Figure 1 is a view partly in elevation and 50 partly in vertical section illustrating a crutch attachment embodying the invention; Figure 2 is a horizontal view taken substantially on the line 2—2 of Figure 1 looking in the direction indicated by the arrows;

Figure 3 is a similar view taken on the line 3—3 of Figure 1 looking in the direction indicated by the arrows;

Figure 4 is a view partly in elevation and

partly in section illustrating the spur member of the attachment.

In Figure 1 of the drawings there is illustrated the lower end of the staff of a crutch indicated by the numeral 1 and the said end of the staff is fitted into a socket 2 formed in the upper portion of the tip attachment which is indicated in general by the numeral 3. The attachment comprises a body which is preferably of the general form shown in the drawings and of approximately the same diameter as the lower portion of the crutch staff and is provided, in addition to the socket 2, with a socket 4 which is located in its lower end, the portion of the tip between the bottom of the socket 2 and the upper end of the socket 4 being solid, as indicated by the numeral 5. One or more screws or other fastening devices 6 are secured through the wall of the socket 2 and into or against the lower end of the crutch staff and secure the attachment to the said staff.

To adapt the crutch for use upon normal surfaces, a pad 7 is provided and is preferably of frusto-conical form as shown in Figure 1, the pad being reduced at its upper end as indicated by the numeral 8 so as to fit in the socket 4 as shown in the said figure and Figure 2, screws or other fastening elements 9 being secured through the wall of the socket 4 and into or against the said reduced upper end of the pad. In reducing the upper end of the pad, a circumferential shoulder 10 is provided which abuts against the lower edge of the wall of the said socket 4 as shown in Figure 1 thus affording a firm foundation for the pad. The pad may be made of rubber or any other material or combination of materials found suitable for the purpose and it preferably is provided with a flat under face indicated by the numeral 11 which is to contact the surface over which the user of the crutch is moving.

The solid portion 5 of the attachment is provided with a diametric bore which is indicated by the numeral 12, and rotatably adjustably fitted in this bore is the shank 13 of the spur member of the attachment, which member is indicated in general by the numeral 14. The spur comprises a body 15 from the upper end of which the shank 13 extends at right angles. The body 15 at its juncture with the shank 13 is provided with an enlargement 16 having a substantially flat face 17 which is provided with radial corrugations or ribs 18. These

corrugations or ribs are designed to interlock with similar corrugations or ribs 19 formed upon the face of a flattened portion 20 of the body of the tip 3. The lower 5 end of the body 15 is tapered or otherwise brought to a point indicated by the numeral 21. As previously stated the shank 13 is rotatably adjustable in the bore 12 and it will be evident by reference to Figure 1 10 of the drawings that when the spur member is adjusted to assume the position shown in full lines; the sharp end 21 thereof will project a greater or less distance below the flat underface 11 of the pad 7, and when 15 the said member is adjusted to the position shown in dotted lines, the pointed end will be presented in an upward direction. The shank 13 projects through one end of the bore 12 and is threaded as indicated by the 20 numeral 22, and a thumb nut 23 is threaded onto this end of the shank and adapted to bear against the body of the attachment at a point opposite the flattened portion 20. It will now be evident that by loosening the 25 thumb nut, the shank 13 may be shifted laterally within the bore 12 a distance sufficient to disengage the ribs 18 from the ribs 19 whereupon the body 15 of the spur member may be swung to either position 30 of adjustment desired. Then by tightening the nut 23, the ribs 18 and 19 will again be caused to interlock and the spur member will be securely held in the position to which it has been adjusted.

35 Having thus described the invention, what is claimed as new is:

1. A crutch tip comprising a body having means for attachment to a crutch staff and provided with an intermediate thickened portion pierced by a transverse bore, a spur member comprising a body having an engaging end and provided at its opposite end with a laterally extending shank rotatably adjustably fitted in the said bore 40 whereby the body of the spur member may be angularly adjusted to assume active and inactive positions, and means coacting with the shank to hold the body of the spur member in its positions of adjustment.

50 2. A crutch tip comprising a body having

upper and lower sockets, one of which is adapted to receive a crutch staff, the body having a transverse bore located between said sockets and being provided upon its outer side at one end of the bore with a 55 roughened surface, a cushioning member mounted in the lower socket, a spur member comprising a spur body having one end pointed and provided at its other end with a laterally extending shank and with a 60 roughened surface extending about the shank, the said shank being rotatably adjustably fitted into the said bore, the other end of the shank extending beyond the opposite side of the body of the crutch tip 65 and being threaded, and a nut fitted onto the said end of the said shank and bearing against the said body for holding the pointed end of the spur in either active or inactive positions.

3. A crutch tip comprising a body having upper and lower sockets, one of which is adapted to receive a crutch staff, a cushioning member mounted in the lower socket, and a spur member having a shank rotatably mounted in the body between said 70 sockets and provided with an engaging end movable to active position below the lower side of the said cushioning member.

4. A crutch tip comprising a body having 75 means for attachment to a crutch staff and provided with an intermediate thickened portion pierced by a transverse bore, the exterior wall of the body member at one end of the bore being roughened, a spur 80 member comprising a shank rotatably mounted in the bore and having one end thereof threaded and its other end provided with a depending portion terminating in a spur, there being a roughened portion 85 at the junction of the shank and depending portion, and a clamping nut engaging the threaded end of the shank and bearing against the adjacent portion of the body 90 for causing the roughened portions to interengage and hold the spur in either active or inactive positions.

In testimony whereof I affix my signature.

JAMES B. MORFITT, [I. S.]
